COKING RETORT OVEN

Joseph Becker, O'Hara Township, Allegheny County, Pa., assignor to The Koppers Company of Delaware, a corporation of Delaware

Application January 19, 1932, Serial No. 587,541

1 Claim. (Cl. 202—142)

My invention relates to coking retort ovens and particularly to heating systems therefor.

The subject-matter of the present application is closely related to that of my Patent No. 5 1,374,546, upon which the present invention is an improvement.

In the structure of my prior patent, I provide crossover flues which extend over an oven chamber for connecting the horizontal flues of the heating walls adjacent to the oven chamber in order to connect the heating systems of these walls for operation in series with each other. All of the heating walls of the battery are similarly connected in pairs.

15 In each of the heating walls of the structure covered by my prior patent, the gases of combustion pass upwardly from the flame flues in which combustion occurs, through ports or ducts into a horizontal flue within which they flow horizontally to one of the crossover flues for distribution through a similar system in an adjacent wall.

20 The tops of the flame flues operate as baffles and the flames of combustion are extinguished as the gases pass through the ducts into the horizontal flues. Accordingly, the temperature of the gases above the top of the flame flues is not sufficiently high to be useful in coking and the tops of the flame flues constitute the upper limit of the useful heating surface for the adjacent oven chamber.

25 In accordance with the present invention, I am enabled to eliminate the horizontal flues above the flame flues in each of the heating walls. The flame flues are extended upwardly 30 to occupy the space formerly required by the horizontal flues and their connections to the flame flues.

35 The result is to materially increase the heating surface of the flame flues of each heating wall. The structure of the heating walls is greatly simplified since the relatively simple arrangement of the flame flues is substituted for the arrangement of the horizontal flues and the ducts for connecting them to the flame flues.

40 Also, the elimination of these ducts and the resulting reduction in the number of changes in direction of the gases facilitates their flow by reducing the resistance to such flow. The drop 45 in pressure of the gases through these portions of the heating system is reduced by the elimination of the resistance to their flow.

45 The coke-oven battery embodying my invention comprises other features of construction and arrangement which will be described in connection with the accompanying drawings, in which

Figure 1 is a view in transverse vertical section of a coke-oven battery constructed in accordance with my invention;

Fig. 2 is an enlarged view in vertical longitudinal section of a portion of the battery of Fig. 1; 5

Fig. 3 is an enlarged vertical sectional view of a portion of the heating wall shown in Fig. 1; and

Fig. 4 is a vertical sectional view of a portion of a coke-oven battery in which horizontal distributing ducts for rich gas are employed.

50 Referring particularly to Figs. 1, 2 and 3, a coke-oven battery 1 comprises any suitable number of horizontal oven chambers 2 and heating walls 3 therefor that alternate therewith. The 15 battery is provided with a roof or top 4, through which extends the usual charging holes 5, three of which are shown by way of example.

Each oven chamber is also provided with a gas offtake opening 6 at each end thereof. An 20 ascension pipe 7 connects each gas offtake opening 6 to a collecting main 8 one of which extends along each side of the battery.

25 Horizontal brickwork 10, which extends beneath the oven chambers 2 and heating walls 3, separates the latter from the regenerator structure therebeneath. The regenerators consist of two rows of crosswise regenerators 11, each of which extends half the width of the battery. The battery structure is supported upon a foundation comprising a pad 12, pillars 13 and a base 14, which may be of concrete. This arrangement provides passageways for convenient access to the bottom portion of the battery structure.

30 Each regenerator 11 is provided with a sole 35 flue 15, to which is connected a reversing box 16. Producer gas is supplied to the battery from a main 17 on each side of the battery. The mains 17 are connected through valves 18 to the reversing boxes 16 that supply fuel gas when the corresponding regenerators operate as inflow regenerators.

35 When rich gas, such as coke-oven gas, is used as fuel, it is supplied from a main 19 that is connected to a header 20 for each of the heating walls 3. Each of the headers is, in turn, connected by means of vertical ducts 21, which extend through the walls of the regenerators 11 for supplying gas to the heating wall. This system of supplying rich gas is known as the underburner system since the various headers and the controlling valves 22 therefor, as well as the adjusting valves 23 for the vertical ducts, are all located in galleries or tunnels 24 beneath the 40 battery structure.

Each of the heating walls 3 is provided with a series of vertical flame flues 26 that may be of any suitable number, twenty-seven being shown by way of example.

- 5 As best shown in Fig. 3, certain of the partition walls 27 of the flame flues do not extend to the roof of the battery whereby lateral or horizontal flow of the gases of combustion adjacent to the roof of the battery is permitted. At the 10 top of the other partition walls 27 is an opening 28 that is preferably rectangular in shape, which extends through the bottle-bricks of the wall to permit communication between adjacent flame flues 26.
- 15 As best shown in Fig. 3, the top edges of the short walls are rounded while the edges beneath the openings 28 are tapered in order to facilitate the changes in direction of the flow of gases. The 20 row of openings 28 and the top portions of the flame flues constitute in effect a horizontal flue since horizontal flow of gases may occur along the tops of the heating wall.

At intervals along the length of the oven and 25 preferably so distributed as to divide the flame flues into groups of approximately four flame flues each, are a series of crossover flues 29 that extend from the horizontal space along the top of one heating wall across the intervening oven 30 chamber 2 to the similar horizontal space of the adjacent heating wall. It will be noted that the ends of the crossover flues 29 are substantially in alignment with the short partition walls 27 in order to equalize the flow of gases through the 35 group of flues in series with the crossover flue.

35 While the space along the top of the heating wall that connects the several flame flues to each other and to the crossover flues 29 is substantially continuous, the omission of certain of the openings 28 would serve to divide the flame flues into 40 groups communicating with the crossover flues 29 connected to that group. However, the present arrangement provides that, in case of differences in pressure in adjacent groups, such differences may be equalized by means of the transfer of 45 gases along the horizontal space which also connects adjacent crossover flues.

In the operation of the battery, it may be assumed that producer gas is being supplied from the mains 17 through the corresponding reversing boxes 16 and that air is being supplied to certain of the regenerators through similar boxes 18. Air and gas then flow through the inflow regenerators and through inclined ducts 30 and ports 31 for combustion in one heating wall of 50 each connected pair. The gases burn upwardly in the flame flues and the resulting gases of combustion, when they reach the top of the latter, flow either to the right or to the left, as the case 55 may be, through the openings 28 to the most nearly adjacent crossover flue 29.

The gases of combustion flow through the several crossover flues and are then distributed through the several openings 28 into the flame flues 26 of the co-operating heating wall, in which 60 they flow downwardly and out through inclined ducts 30 into outflow regenerators 11. They then pass through the corresponding reversing boxes 16 and vertical ducts 33 into waste gas mains 34 that are connected to the usual stack (not 70 shown).

Each of the crossover flues 29 is provided with sliding bricks 35 for regulating the flow of waste gases therethrough. The distribution and relative flow of gases through the various parts of the system may be controlled by these regulating 75

bricks. Each flame flue 26 is provided with an inspection opening 36 extending through the roof 4 and each inspection opening is provided with a cover brick 37.

The arrangement of the regenerators for transmitting air and gas and waste gases when the direction of flow within the several heating walls is as indicated by the arrows in Fig. 2 is shown by the respective legends A, G and WG in full lines designating the respective regenerators. It 10 will be noted that the regenerators are divided into groups of three, the central regenerator of each group being larger than the other two.

When a group operates as inflow regenerators, the central or large regenerator supplies producer 15 gas to two heating walls while each of the smaller or outer members of the group supplies air to one of the two heating walls. When a group operates as outflow regenerators, all of the members 20 of the group carry waste gas.

This arrangement provides that an air regenerator is always between regenerators carrying fuel gas and waste gases. Counterflow between these gases is thus prevented. Also, this arrangement of regenerators in groups provides that no 25 pillar wall is necessary under alternate oven chambers and additional regenerator space is thus provided.

The direction of flow of gases through the battery is periodically reversed at the end of periods 30 of substantially a half hour. When the direction of flow is opposite to that of the arrows shown in Fig. 2, the regenerators operate to carry air, gas or waste gases in accordance with the arrangement shown by the legends in dotted lines in Fig. 35. 2. It will be noted that the same relation of air regenerators with respect to gas regenerators and waste-gas regenerators obtains that was described in connection with the operation of the gases in the other direction.

When rich gas or coke-oven gas is employed as fuel, the connections to the producer gas mains are closed and all of the inflow regenerators during any reversal period, operate as air regenerators and all of the outflow regenerators carry 45 waste gases, as in the previous operation. Coke-oven gas is supplied to all of the flame flues of the walls in which combustion occurs by means of the headers 17 and the vertical ducts 21 that extend directly into the flame flues 26. It will be 50 noted that no nozzles are required for regulating the flow of gas, such regulation being accomplished by the valves 23 beneath the battery.

Reference may now be had to Fig. 4, in which is illustrated modified apparatus for supplying 55 rich gas for heating the oven. The additional structure comprises a rich gas main 39, extending along the side of the battery, and that is connected by means of valves 40 and gas guns 41 to horizontal ducts 42 that extend through the 60 horizontal brickwork 10 beneath each of the heating walls. Short vertical ducts 43 comprising the usual nozzles (not shown) connect the horizontal duct 42 to each of the flame flues 26.

When rich gas is employed in the apparatus 65 illustrated in Fig. 4, the arrangement of the regenerators and the operation of the heating system is otherwise as described in connection with the supplying of rich gas through the under-burner system of Figs. 1, 2 and 3.

The construction of coke-oven batteries in accordance with my invention is materially more simple than that in which it has been necessary to provide separate horizontal flues for each heating wall and to provide ducts for connecting each 75

flame flue to a horizontal. The area of useful heating surface has been increased by extending the flame flues to include the space formerly occupied by such ducts and horizontal flues.

5 Since the path of travel for the gases of combustion offers considerably less resistance to the flow of gases through the battery, the drop in pressure has been correspondingly diminished and the efficiency of the operation of the heating system has thus been improved.

10 By means of the provision of sliding bricks in the several crossover flues, regulation or adjustment between the groups of flame flues of any pair of heating walls is readily effected. Since 15 the crossover flues are connected at each end through the tops of the flame flues, differences in pressure may be equalized by the division of the gases between the crossover flues and the distribution of the gases in the adjacent heating wall.

20 The provision of means beneath the battery for supplying rich gas enables the latter to be regulated at points accessible to the operators and the use of nozzles or sliding bricks for the individual flues is unnecessary. Also, the elimination of one-half of the pillar walls has materially increased the amount of regenerator space that is available.

25 The foregoing and other advantages will be apparent to those skilled in the art of construction and operation of coke-oven batteries.

30 I claim as my invention:

A horizontal coke oven comprising a horizontal coking chamber and combustion heating means therefor comprising two heating walls on opposite 35 sides of the oven chamber, each of said heating walls having a series of vertical flame flues therein arranged in a row parallel with the oven chamber with partition walls between said flame flues and the tops of the partition walls and the top of the 40 heating wall providing between them a horizontal gas flow space along the top of the heating wall

and communicably connecting the upper parts of the flame flues in the heating walls, a plurality of crossover flues extending over said oven chamber and communicating with the horizontal gas flow space at the upper parts of the flame flues in each heating wall to communicably connect the flame flues of said heating walls in series, said crossover flues being spaced from each other so that each of them is communicably connected at each end thereof with vertical flame flues on opposite 10 sides thereof along the heating walls and so that each of the crossover flues may be required to accommodate gas flow to and from substantially only a part of the vertical flues that communicate with the horizontal gas flow space between 15 each two crossover flues, the effective cross-sectional area of the aforesaid horizontal gas flow space being substantially less than the effective cross-sectional area of the vertical flame flues, for accelerating velocity of gas flow laterally over 20 the flame flues to the crossover flues, and the vertical flame flues being free from gas throttling constrictions, where they communicate with the horizontal gas flow space, that would cause an increase in pressure to enable the gas to flow 25 through such constrictions out of the flues into the horizontal gas flow space and into the flues from the horizontal gas flow space, and said vertical flame flues communicating at their upper parts with the crossovers solely through the horizontal gas flow space and non-regulable connections of the vertical flues with the horizontal gas flow space, whereby the gas flow through the horizontal gas flow space will be accelerated directly towards the crossovers by the direct deflection of the upward discharging from the vertical flues directly towards the crossovers and substantially free from pressure-inducing restrictions below the crossovers.

JOSEPH BECKER. 40
